COLLAPSIBLE ARMCHAIR

Leto J. Garbaccio, North Bergen, N. J.

Application June 19, 1937, Serial No. 149,193

4 Claims. (Cl. 155—148)

The invention relates to collapsible armchairs and has for its main purpose to produce an armchair which may readily be folded up so as to occupy very small space. Another object is to construct the chair so light in weight that it may easily be carried from place to place. A further object is to so proportion and construct the seat and back rest of the chair that, when the chair is folded, they will act as covers for the chair itself so that the chair will practically be enclosed in these parts.

A still further object is to so construct the chair that it may be set up or folded with minimum expenditure of labor and without the requirement of any great skill by the operator. Additional objects are to construct a chair of this type which, while very light in weight, will still be strong and rigid and able to support a heavy weight; which is neat in appearance; and which can be manufactured at a relatively low cost.

These and various other objects and advantages will be readily understood from the following description and from the accompanying drawing of a preferred embodiment of the invention, in which, however, modifications may be made without departing from the scope of the appended claims. In the drawing,

Fig. 1 is a side view of the chair shown set up for use;

Fig. 2 is a front view of same;

Fig. 3 is a plan view;

Fig. 4 is a fragmental, plan view of the seat and one of its supporting members;

Fig. 5 shows one of the steps employed in folding the chair; and

Fig. 6 shows the chair folded to the position in which ordinarily carried.

Referring now to all the views simultaneously, the chair consists of four tubular legs 10. On each side of the chair a pair of braces 11 and 12 have their lower ends pivoted, as at 13 and 14, near the lower ends of the legs. These braces are also pivoted where they cross at 15 and their upper ends are pivoted at 16 and 17 to two arms 18 and 19, which in turn are pivoted to the legs at 20 and 21. The free ends of the arms 18 and 19 are provided with sidewardly-extending detents 22 and 23, which prevent the legs from being spread further than to the position shown in Fig. 1.

Referring now particularly to Fig. 2, a brace 24 is pivoted at 25 near the lower end of one of the legs, while the upper end of this brace is pivoted at 26 to a sleeve 27 slidably mounted on the other leg. A similar brace 28 has its lower

end pivoted at 29 to the leg on which the sleeve 27 slides, while its upper end is pivoted at 30 to another sliding sleeve 31, which is free to slide on the leg to which the lower end of the bracket 24 is pivoted. When the chair is spread as far apart as shown in Fig. 2, the sleeves rest on the arm 19, as plainly shown in Fig. 2, so that the legs cannot be spread any further. The braces 24 and 28 are pivoted at the center by a shouldered rivet 32. This rivet is plainly shown in Fig. 3. Similar braces are employed on the rear of the chair and are similarly numbered.

The seat 33 is preferably made of heavy canvas or other suitable material. Hems are made on opposite sides of the seat and in these hems spacing bars 34 are inserted. The outer ends of these spacing bars are provided with bifurcated members 35 and 36 which fit over the front and rear legs and which, when the seat is in place, rest on top of the sliding sleeves 27 and 31. The spacing bars are made of such length that they will hold the legs in exactly the same position as the braces allow the legs to be parted. A fitting 37 is placed on the upper end of each rear leg and another fitting 38 on the upper end of each front leg. Leather straps 39 have their rear ends permanently secured to the fittings 37 by means of rivets 40, while the front end of the leather straps pass over the fittings 38 which are provided with semi-circular tops 41.

A clamp 42 is swingably mounted on the fitting 38 and two buttons 43 are riveted on the leather straps themselves, so that any weight placed on the leather straps will cause the buttons to engage with the clamp 42 and clamp it against the fitting 38. A back rest 44 is preferably made of canvas and is mounted on the upper end of two levers 45. The lower ends of these levers are pivoted to the arms 18. The levers are supported in an angular groove 46 extending sidewardly from a slot 47 formed in the fitting 37. This slot prevents rearward displacement of the back rest and secures it firmly to the chair when this is set up as shown.

The manner in which the chair is folded is best illustrated in Figs. 2 and 5. The first step is to remove the seat by pulling out the spacing members 34. Next the side legs are pushed towards each other as indicated by the arrows 48 and 49 in Fig. 2. This causes the sleeves 27 and 31 to occupy the positions right up under the fittings 37 and 38, as shown in Fig. 5. The front and rear legs are next pushed together as indicated by the arrows 50 and 51 in Fig. 5. As the front and rear legs are pushed together the back rest levers 55

45 are pushed upwardly and consequently out of the groove 46. At the same time the straps 39 are drawn down over the front legs as shown.

After the front and rear legs have been folded 5 completely together, the back rest is swung down, as indicated by the dotted lines 52 until they rest against the rear legs. All of the parts are now completely folded up. The next step is to fold 10 the canvas of the back rest 44 around the folded part, as shown in Fig. 6. After this the canvas seat 33 is folded around the uncovered part, as 15 also shown in Fig. 6 and finally a carrying strap 53 is secured around the package formed.

From the foregoing it will be seen that this 15 chair is easy to fold and easy to set up, and then, when folded, will occupy but very small space so that it may readily be carried from place to place.

Having described the invention and its objects, 20 what I claim as new and wish to protect by Letters Patent is:—

1. A collapsible chair of the class described comprising four leg members; crossed braces secured on opposite sides of the chair; the lower ends of said braces pivoted near the lower ends 25 of the legs and the upper ends to arms also pivoted to the legs; the crossed braces pivoted at the points where they overlap each other; detents formed on the arms for engagement with the braces when the front and rear legs are separated 30 the desired distance; crossed braces secured to the front and rear legs with their lower ends pivoted near the lower ends of the legs and their upper ends pivoted to sleeves slidably mounted on the legs; pivots likewise inserted in these 35 braces where they overlap each other; the sliding sleeves adapted to rest on the arms connected with the side braces when the legs are separated the required distance; spacing bars, having bifurcated end members for engagement with the front 40 and rear legs and adapted to rest on the sleeves; a fabric seat secured on said spacing bars; and the spacing bars made of such length as to hold the front and rear legs separated the required 45 distance.

2. A collapsible chair of the class described 50 comprising four leg members; crossed braces secured on opposite sides of the chair; the lower ends of said braces pivoted near the lower ends of the legs and the upper ends to arms also pivoted to the legs; the crossed braces pivoted at the points where they overlap each other; detents formed on the arms for engagement with the braces when the front and rear legs are separated 55 the desired distance; crossed braces secured to the front and rear legs with their lower ends pivoted near the lower ends of the legs and their upper ends pivoted to sleeves slidably mounted on the legs; pivots likewise inserted in these braces where they overlap each other; the sliding sleeves adapted to rest on the arms connected with the side braces when the legs are separated the required distance; spacing bars, having bifurcated end members for engagement with the front 60 and rear legs and adapted to rest on the sleeves; a fabric seat secured on said spacing bars; the spacing bars made of such length as to hold the front and rear legs separated the required distance; and two side bars, having their lower ends pivoted to the rear arms on the sides of the chair 65 and their upper ends secured to a fabric back-rest, adapted to be held in an inclined position in slotted fittings secured on the upper ends of the rear legs; and two straps, attached to said slotted fittings and clamped to fittings secured on top of the front legs, for forming a pair of arm rests.

in slotted fittings secured on the upper ends of the rear legs.

3. A collapsible chair of the class described 70 comprising four leg members; crossed braces secured on opposite sides of the chair; the lower ends of said braces pivoted near the lower ends of the legs and the upper ends to arms also pivoted to the legs; the crossed braces pivoted at the points where they overlap each other; detents formed on the arms for engagement with the braces when the front and rear legs are separated 75 the desired distance; crossed braces secured to the front and rear legs with their lower ends pivoted near the lower ends of the legs and their upper ends pivoted to sleeves slidably mounted 80 on the legs; pivots likewise inserted in these braces where they overlap each other; the sliding sleeves adapted to rest on the arms connected with the side braces when the legs are separated the required distance; spacing bars, having bifurcated end members for engagement with the front 85 and rear legs and adapted to rest on the sleeves; a fabric seat secured on said spacing bars; the spacing bars made of such length as to hold the front and rear legs separated the required distance; two side bars, having their lower ends pivoted to the rear arms on the sides of the chair 90 and their upper ends secured to a fabric back-rest, adapted to be held in an inclined position in slotted fittings secured on the upper ends of the rear legs; and two straps, attached to said slotted fittings and clamped to fittings secured on top of the front legs, for forming a pair of arm rests.

4. A collapsible chair of the class described 95 comprising four leg members; crossed braces secured on opposite sides of the chair, the lower ends of said braces pivoted near the lower ends of the legs and the upper ends to arms also pivoted to the legs; the crossed braces pivoted at the points where they overlap each other; detents formed on the arms for engagement with the braces when the front and rear legs are separated 100 the desired distance; crossed braces secured to the front and rear legs with their lower ends pivoted near the lower ends of the legs and their upper ends pivoted to sleeves slidably mounted on the legs; pivots likewise inserted in these braces where they overlap each other; the sliding sleeves adapted to rest on the arms connected with the side braces when the legs are separated the required distance; spacing bars, having bifurcated end members for engagement with the front 105 and rear legs and adapted to rest on the sleeves; a fabric seat secured on said spacing bars; the spacing bars made detachable from the legs and of such length as to hold the front and rear legs separated the required distance; two side bars, having their lower ends pivoted to the rear arms on the sides of the chair and their upper ends secured to a fabric back-rest, adapted to be held 110 in an inclined position in slotted fittings secured on the upper ends of the rear legs; two straps, attached to said slotted fittings and clamped to fittings secured on top of the front legs, for forming a pair of arm rests; and the fabric seat and back rest so proportioned to the size of the chair that they will act as a cover for all the parts of the chair when the seat and spacing bars are removed, the back-rest side bars folded down, and the other parts of the chair collapsed.

LETO J. GARBACCIO.
